Primary Examiner — Rosemary K Tarcza*(74) Attorney, Agent, or Firm* — Christopher R. Balzan; Eric J. Agaard(57) **CLAIM**

The ornamental design for an electric vehicle charger, as shown and described.

DESCRIPTION

FIG. 1 is a front-right-top perspective view of an embodiment of an electric vehicle charger;

FIG. 2 is a front view of the electric vehicle charger of FIG. 1;

FIG. 3 is a right side view of the electric vehicle charger of FIG. 1;

FIG. 4 is a left side view of the electric vehicle charger of FIG. 1;

FIG. 5 is a rear view of the electric vehicle charger of FIG. 1;

FIG. 6 is a top view of the electric vehicle charger of FIG. 1;

FIG. 7 is a bottom view of the electric vehicle charger of FIG. 1; and,

FIG. 8 is a back-left-top perspective view of the electric vehicle charger of FIG. 1.

The broken lines in FIGS. 1–8 and the unshaded region therein are for illustrative purposes only and form no part of the claimed design of the respective embodiment.
